Albert Osborn Baker, of Providence, Rhode Island.

Letters Patent No 1849 - Dated Nov. 17th 1863.

Design for a Belt Fastener.

The schedule referred to in these letters Patent and making part of the same.

To all whom it may concern:

Be it known that I, Albert Osborn Baker, of the City and County of Providence, in the State of Rhode Island, have invented a new and original design for Ladies Belt Hooks; and I do hereby declare that the following specification, taken in connection with the drawings making a part of the same, is a full, clear and exact description thereof.

Figure 1. is a view of the new design.

Figure 2. is a cross section through the short diameter.

Figure 3 is an end view.

The new design represented in the accompanying drawings consists of two oval disks of gold plate or plate metal, the long diameter being about twice the length of the short diameter - a raised rim

Dec. 1849

of filagree work surrounds the edge and is for the purpose of receiving the enamel which constitutes a principal portion of the face. The central portion is of the same kind of metal as the edge before described and is of the same contour as the outer edge and is raised flush with the face of the enamel, so

that the appearance of each disk is that of a central oval of metal surrounded by a belt of enamel the whole enclosed within a metallic rim of ornamental work. Each disk is furnished with the usual wire attachment to which the ends of the belt can be secured, and one of the disks has a hook and the other an eye which when united are concealed by the overlapping of the discs from view.

What I claim as new and desire to secure by Letters Patent, is,-

The design for a belt fastener shown and described consisting of a central metallic oval relieved by a belt of enamel of the same external contour and the whole surrounded by an ornamental metallic rim as shown in the drawings.
